UNITED STATES PATENT OFFICE

165,401

OPHTHALMIC MOUNTING OR THE LIKE

Edward M. Splaine, Southbridge, Mass., assignor to American Optical Company, Southbridge, Mass., a voluntary association of Massachusetts

Application February 10, 1950, Serial No. 7,858

Term of patent 14 years

(Cl. D57—1)

To all whom it may concern:

Be it known that I, Edward M. Splaine, a citizen of the United States of America, residing at Southbridge, in the county of Worcester, and State of Massachusetts, have invented a new, original and ornamental Design for an Ophthalmic Mounting or the like, of which the following is a specification, reference being made to the accompanying drawings, forming a part thereof.

Fig. 1 is a front elevation view of an ophthalmic mounting, showing my new design; and

Fig. 2 is a top plan view of the mounting shown in Fig. 1.

The characteristic features of my design are shown in full lines in the drawing.

I claim:

The ornamental design for an ophthalmic mounting or the like, substantially as shown and described.

EDWARD M. SPLAINE.
